UNITED STATES PATENT OFFICE.

ALOIS BENJAMIN SALIGER, OF NEW YORK, N. Y., ASSIGNOR TO BECK DUPLICATOR COMPANY, A CORPORATION OF NEW YORK.

DUPLICATOR.

1,270,331.

Specification of Letters Patent. Patented June 25, 1918.

Application filed July 7, 1916. Serial No. 108,037.

To all whom it may concern:

Be it known that I, ALOIS BENJAMIN SALIGER, a citizen of the United States, and a resident of the borough of Manhattan, in 5 the city and State of New York, have invented certain new and useful Improvements in Duplicators, of which the following is a specification.

The invention relates to duplicators, and 10 more particularly to that type of duplicators in which a negative or reversed impression of the matter to be copied is transferred upon a gelatinous duplicating surface or the like, after which sheets of paper 15 upon which copies are to be made are brought into contact therewith; and it has for one of its principal objects to produce such a duplicator which may be simply and cheaply constructed; and which shall be capable of easy, smooth, and rapid operation.

The invention consists in the novel construction, arrangement and combination of various devices, elements and parts, as 25 shown in the accompanying drawings and fully described in this specification.

In the said drawings, Figure 1 is a side elevation of my invention; Fig. 2 is a rear elevation of the same, showing the parts in another position; Fig. 3 is a section taken 30 on the line 3—3 of Fig. 2 and looking in the direction of the arrows, showing the parts in still another position; and Fig. 4 is a detail view to be hereinafter described.

In carrying my invention into effect in 35 the embodiment thereof which I have selected for illustration in the accompanying drawings and description in this specification, I provide a base 11, bearing uprights 12, in which is journaled a shaft 13, rotatable by means of a crank 15 having a handle 14. Rigidly mounted on the shaft 13, between the uprights 12, I provide a rotary frame comprising side members 16 and a curved bed 19. One of the members 16 is 40 provided with a series of holes 17, whose purpose will be hereinafter described, and the other member 16 bears a rack 18. Adjacent each end of the bed 19 I provide a small roller 20.

50 Mounted in the rotary frame are two rollers 21, around which is wound the ends and portion not in use of a strip of gelatinous duplicating film or the like 22. Each roller is provided at one end with a ratchet

23. I provide pawls 24 adapted to engage 55 with said ratchets, said pawls being pivoted at 25 to levers 26, and also connected to said levers by means of springs 29. The levers 26 are connected together at their inner ends by means of a handle 27 pivotally 60 secured to said levers, by means of which handle the levers may be operated and the pawls 24 thrown into or out of engagement with the ratchets 23. A friction washer 30 is provided for the purpose of holding the 65 levers 26 tightly together and pressing the same against the handle 27, in order that the levers may remain in whatever position they may be placed by the operation of the said handle. I provide two guard plates 70 28, parallel to and adjacent the members 16, which guard plates are adapted to prevent the duplicating film 22 from being displaced, and one of which plates is provided with a slot through which the handle 27 may pass. 75

Integral with the members 12 are extensions 31, which extensions have journaled therein an impression roller 32, adapted to bear against the duplicating surface 22 when the rotary frame is moved, and which roller 80 is provided with a gear wheel 33 rigidly attached to one end and adapted to engage with the rack 18. A second roller 34 bears against the roller 32, and its pressure thereupon may be adjusted by means of screws 37, 85 which regulate springs 36, bearing upon blocks 35, which in turn press upon the end bearings 38 of the roller 34. (See particularly Fig. 4). In a similar manner, the pressure of the roller 32 upon the duplicating film may be regulated by means of screws 39, springs 40, and blocks 41. Rigidly 90 secured to the extensions 31 is a shelf 42, adapted to receive paper to be fed into the duplicator. A sheet of paper is shown upon 95 this shelf and designated 43.

On the rotary frame is a stop 45 adapted to limit the movement of the said rotary frame in one direction by engagement with a portion of one of the members 12, a cushion stop 44 being provided if desired. The rotation in the other direction of the rotary frame is limited by an adjustable stop 46, mounted on the end of a spring lever 47, which lever 47 is provided at its 100 other end with a ring 48, whereby it is adapted to be rotatably mounted upon the shaft 13. The stop 46 may be moved oppo-

site any of the holes 17, and will be held in engagement therewith by the spring lever 47. This stop 46 is adapted to strike against a cushion stop 49 located on the extension 31.

5 The operation of my invention is as follows: In order to insert or remove a strip of duplicating film, the parts are turned into the position shown in Fig. 2, in which the rollers 21 are readily accessible from the rear. The end of the strip is secured to one of these rollers, and the rotary frame is then turned into the position shown in Fig. 1, in which position the duplicating film may be passed over the bed 19 without the impression roller 32 being in the way. The film is then passed over one of the rollers 20, around the bed 19, and over the other roller 20, the device returned to the position shown in Fig. 2, and the free end of the duplicating film secured to the other roller 21. The relative positions of the rotary frame and the duplicating film thereon are best shown in Fig. 3.

25 The pawls 24 are then thrown into engagement with the ratchets 23 and the duplicating film drawn taut over the bed 19 by rotating the rollers 21 by means of cranks 44. When it is desired to move a new portion of the duplicating film over the bed, the 30 pawls 24 are disengaged, the handles 44 manipulated until the desired portion is moved into place, the pawls again placed in engagement, and the film tightened.

35 A sheet of paper upon which is written in suitable ink the matter to be copied is placed upon the shelf 42, and its lower end pushed downward as far as possible upon the rollers 32 and 34, and, the parts being in the position shown in Fig. 1, the handle 40 14 is operated to bring them into the position shown in Fig. 3. The motion of the rotary frame is communicated to the impression roller 32 by means of the rack and gear wheel, and from the impression roller to the 45 roller 34 by friction. The end of the paper is grasped by the rollers 32 and 34, and passed between them upon the duplicating film. The motion of the duplicating film causes the end of the paper to pass between it and the roller 32, and as the rotary frame continues to turn, more and more of the 50 paper is brought into contact with the duplicating surface.

55 The motion of the rotary frame is stopped at such a point that when the paper upon which copies are to be made is inserted in the machine, a small portion of the last inserted end shall remain upon the shelf 42, and not be passed between the rollers 32 and 60 34. The movable stop 46 is then set at such a point that the motion of the rotary frame will be automatically stopped at this place. The movement of the handle 14 is then reversed, and the parts returned to the position shown in Fig. 1, reversing the move-

70 ment of the impression roller 32, and causing it to eject the paper upon the shelf 42. Each sheet of paper upon which a copy is to be made is manipulated in the same manner as the sheet containing the original matter, as will be readily understood.

75 The advantages of my invention will be obvious from what has been above set forth concerning its construction and mode of operation. I do not limit myself to the exact form described, as it is obvious that various modifications might be made therein, without departing from the spirit and scope of my invention. For instance, the relative 80 positions of the parts might be so arranged that the paper, after passing between the rollers 32 and 34, would travel upward instead of downward, in which case the roller 34 would become the impression roller, and would be so set as to bear against the duplicating film. Another possible modification 85 is the insertion of a paper guide adapted to deflect the paper upward or downward as desired, immediately after it passes between the rollers 32 and 34. It will also be readily 90 understood that the invention might be so constructed that the frame bearing the duplicating surface would remain stationary, and the part of the device carrying the impression roller be reciprocated thereover. 95

Having thus described my invention what I claim as new and desire to secure by Letters Patent is as follows:

1. In a duplicator, the combination with a 100 stationary frame and a rotary frame, a stop on one of said frames adapted to engage with the other of said frames and prevent the complete revolution of said rotary frame, of a duplicating surface mounted on one of said frames, and a pair of rollers mounted 105 on the other of said frames, one of said rollers being adapted when rotating in one direction to bring paper in contact with said duplicating surface and said rollers being adapted when said first named roller is rotating in the other direction to remove said paper from contact with said duplicating surface.

110 2. In a duplicator, the combination with a stationary frame and a rotary frame, a stop on one of said frames adapted to engage with the other of said frames and prevent the complete revolution of said rotary frame, of a duplicating surface mounted on one of 115 said frames, a rack mounted on said frame, and a roller mounted on the other of said frames provided with a gear wheel adapted to engage with said rack, said roller being adapted when rotating in one direction to bring paper in contact with said duplicating surface, and when rotating in the other direction to remove said paper from contact with said duplicating surface.

120 3. In a duplicator, the combination with a stationary frame and a rotary frame, a stop 125

on one of said frames adapted to engage with the other of said frames and prevent the complete revolution of said rotary frame, of a duplicating surface mounted on one of 5 said frames, a rack mounted on said frame, and a pair of rollers mounted on the other of said frames, one of said rollers being provided with a gear wheel adapted to engage with said rack, said first named roller being 10 adapted when rotating in one direction to bring paper in contact with said duplicating surface, and said rollers, when the direction of the rotation of said first named roller is reversed, being adapted to remove said paper from contact with said duplicating surface.

4. In a duplicator, the combination with a stationary frame and a rotary frame, of a duplicating surface mounted on one of said 20 frames, means mounted on the other of said frames and adapted to bring paper in contact with said duplicating surface, an adjustable stop rotatably mounted on one of said frames and adapted to prevent the complete 25 rotation of said rotary frame, and a series of depressions in one of said frames adapted to be engaged by said stop.

5. In a duplicator, the combination with a stationary frame and a rotary frame, of a 30 duplicating surface mounted on one of said frames, means mounted on the other of said frames and adapted to bring paper in contact with said duplicating surface, an adjustable stop rotatably mounted on one of 35 said frames by means of a spring lever, and a series of depressions in one of said frames into one of which a portion of said stop is adapted to be forced by said spring lever.

6. In a duplicator, the combination with a 40 stationary frame and a rotary frame, a stop on one of said frames adapted to engage with the other of said frames and prevent the complete revolution of said rotary frame, of a duplicating surface mounted on one of 45 said frames, a pair of rollers mounted in the other of said frames, one of said rollers being adapted when said roller is rotating in one direction to bring paper in contact with said duplicating surface, and said rollers being 50 adapted when said first named roller is rotating in the other direction to remove said paper from contact with said duplicating surface, and an adjustable spring adapted to regulate the pressure of said rollers 55 upon each other.

7. In a duplicator, the combination with a stationary frame and a rotary frame, a stop on one of said frames adapted to engage with the other of said frames and prevent 60 the complete revolution of said rotary frame, of rollers mounted upon one of said frames and adapted to bear a strip of duplicating material, and a roller mounted on the other of said frames and adapted 65 when rotating in one direction to bring

paper in contact with said duplicating surface and when rotating in the other direction to remove said paper from contact with said duplicating surface.

8. In a duplicator, the combination with 70 a stationary frame and a rotary frame, a stop on one of said frames adapted to engage with the other of said frames and prevent the complete revolution of said rotary frame, of rollers mounted upon one of said 75 frames and adapted to bear a strip of duplicating material, ratchets on said rollers, pawls adapted to engage with said ratchets, and a roller mounted in the other of said frames and adapted when rotating in one 80 direction to bring paper in contact with said duplicating surface and when rotating in the other direction to remove said paper from said surface.

9. In a duplicator, the combination with 85 a stationary frame and a rotary frame, a stop on one of said frames adapted to engage with the other of said frames and prevent the complete revolution of said rotary frame, of rollers mounted upon one of said 90 frames and adapted to bear a strip of duplicating material, ratchets on said rollers, pawls adapted to engage with said ratchets, and means adapted when in one position to hold said pawls in engagement with said 95 ratchets and when in another position to remove said pawls from engagement with said ratchets, and a roller mounted on the other of said frames and adapted when rotating in one direction to bring 100 paper in contact with said duplicating surface and when rotating in the other direction to remove said paper from contact with said duplicating surface.

10. In a duplicator, the combination with 105 a stationary frame and a rotary frame, of a stop on one of said frames adapted to engage with the other of said frames and to prevent the complete rotation of said rotary frame, a duplicating surface mounted on 110 said rotary frame, and a pair of rollers mounted on said stationary frame, one of said rollers being adapted when said rotary frame is rotating in one direction to bring paper into contact with said duplicating 115 surface, and when said rotary frame is rotating in the other direction to remove said paper from contact with said duplicating surface.

11. In a duplicator, the combination with 120 a stationary frame and a rotary frame, of a stop on one of said frames adapted to engage with the other of said frames and prevent the complete rotation of said rotary frame, a duplicating surface mounted on 125 said rotary frame, a rack mounted on one of said frames, and a roller mounted on the other of said frames provided with a gear wheel adapted to engage with said rack, said roller being adapted when said rotary 130

frame is rotating in one direction to bring paper into contact with said duplicating surface and when said rotary frame is rotating in the other direction to remove 5 said paper from contact with said duplicating surface.

12. In a duplicator, the combination with a stationary frame and a rotary frame, of a stop on one of said frames adapted to engage 10 with the other of said frames and prevent the complete rotation of said rotary frame, a duplicating surface mounted on said rotary frame, a rack mounted on said frame, a pair of rollers mounted on said stationary frame, one of said rollers being provided with a gear wheel adapted to engage 15 with said rack, one of said rollers being adapted when said rotary frame is rotating in one direction to bring papers into contact 20 with said duplicating surface and when said rotary frame is rotating in the other direction to remove said paper from said duplicating surface.

13. In a duplicator, the combination with a stationary frame and a rotary frame, of a duplicating surface mounted on said rotary frame, means mounted on said stationary frame and adapted to bring paper into contact with said duplicating surface, an 25 adjustable stop rotatably mounted on one of said frames and adapted to prevent the complete rotation of said rotary frame, and a series of depressions in one of said frames adapted to be engaged by said stop.

35 14. In a duplicator, the combination with a stationary frame and a rotary frame, of a duplicating surface mounted on said rotary frame, means mounted on said stationary frame and adapted to bring paper into contact 40 with said duplicating surface, an adjustable stop rotatably mounted on one of said frames by means of a spring lever, and a series of depressions in one of said frames into one of which a portion of said stop is 45 adapted to be forced by said spring lever.

15. In a duplicator, the combination with a stationary frame and a rotary frame, of a stop on one of said frames adapted to engage 50 with the other of said frames and prevent the complete rotation of said rotary frame, a duplicating surface mounted on said rotary frame, a pair of rollers mounted on said stationary frame, one of said rollers being adapted when said rotary frame is rotating in one direction to bring paper into contact 55 with said duplicating surface, and said rollers being adapted when said rotary frame is rotating in the other direction to remove said paper from said duplicating surface.

cating surface, and an adjustable spring 60 adapted to regulate the pressure of said rollers upon each other.

16. In a duplicator, the combination with a stationary frame and a rotary frame, of a stop on one of said frames adapted to engage 65 with the other of said frames and prevent the complete rotation of said rotary frame, rollers mounted on said rotary frame and adapted to bear a strip of duplicating material, and a roller mounted on said stationary frame and adapted when said rotary frame is rotating in one direction to bring paper into contact with said duplicating surface and when said rotary frame is rotating in the other direction to remove 70 said paper from contact with said duplicating surface.

17. In a duplicator, the combination with a stationary frame and a rotary frame, of a stop on one of said frames adapted to engage 75 with the other of said frames and prevent the complete rotation of said rotary frame, rollers mounted on said rotary frame and adapted to bear a strip of duplicating material, ratchets on said rollers, pawls 80 adapted to engage with said ratchets, and a roller mounted on said stationary frame and adapted when said rotary frame is rotating in one direction to bring paper into contact with said duplicating material and 85 when said rotary frame is rotating in the other direction to remove said paper from said material.

18. In a duplicator, the combination with a stationary frame and a rotary frame, of a stop mounted on one of said frames and adapted to engage with the other of said frames and prevent the complete rotation of said rotary frame, rollers mounted upon 90 said rotary frame and adapted to bear a strip of duplicating material, ratchets on said rollers, pawls adapted to engage with said ratchets, and means adapted when in one position to hold said pawls in engagement with said ratchets and when in another position to remove said pawls from engagement with said ratchets, and a roller mounted on said stationary frame and adapted when said rotary frame is rotating in one direction to bring paper into contact with 95 said duplicating surface and when said rotary frame is rotating in the other direction to remove said paper from contact with 100 said duplicating surface.

In witness whereof I have hereunto 110 signed my name this 5th day of July, 1916.

ALOIS BENJAMIN SALIGER.
